UNITED STATES PATENT OFFICE

JAMES M. JAMESON, OF LOS ANGELES, CALIFORNIA.

PROCESS OF BURNING BRICK.

SPECIFICATION forming part of Letters Patent No. 410,245, dated September 3, 1889.

Application filed May 27, 1889. Serial No. 312,307. (No model.)

To all whom it may concern:

Be it known that I, JAMES M. JAMESON, of Los Angeles, in the county of Los Angeles, State of California, have discovered a new and useful Process of Burning Brick with all Kinds of Coal and with Brea or Crude Petroleum, of which the following is a specification.

The objects of said process are—

First. To facilitate the burning by distributing the fire throughout the kiln and bringing it into immediate contact with the brick, and thereby to shorten the time necessary for burning.

Second. To lessen the labor and expense. When the fire is once kindled, the burning goes on without any further labor of stoking, thus reducing the labor and expense.

Third. To improve the quality of the brick. The fire being distributed throughout the kiln, the brick are burned more uniformly than they can be by the use of wood, and the texture and quality of the brick are regulated by the quantity of fuel used in burning, so that any quality of brick can be obtained which may be desired.

In this process the kiln is formed either as an oblong square or in a circle, at the will of the builder. The floor of the kiln is inclined a little from the outer edges toward the center to prevent it from spreading.

In the accompanying drawings, forming a part hereof, Figure 1 is a view in elevation of a brick-kiln such as may be used in connection with my invention, showing the same as provided with but a single eye or flue. Fig. 2 is a cross-section, and Fig. 3 a vertical transverse sectional elevation, illustrating the proposed manner of arranging the brick and interposed fuel within the kiln according to my invention.

The letter A designates the walls of the kiln; a, the brick, which are placed in the kiln in zigzag rows, as shown in Fig. 2; b, the bed of fuel interposed between each layer of brick, and c the vertical interstices between the brick, also filled with fuel, which interstices are wider at the bottom of the kiln and decrease in width toward the top, as shown in Fig. 3. d indicates the inclined floor of the kiln. The bricks are placed in the kiln in a zigzag manner, as shown in the accompany-

ing diagram, either across the kiln or lengthwise of it, at pleasure, and so far apart as to leave small interstices between the rows of brick, these interstices to be narrowed as the kiln ascends until they entirely disappear. There is but one eye or flue near the end of the kiln, as shown in the diagram, which is formed in the usual way by extending the bricks in building. The kiln is surrounded by a permanent wall as a protection and to confine the heat within the kiln. The fuel is so used and applied throughout the kiln as to fill all the interstices and to cover the entire layer of the brick, so as to form a bed for the next layer of the brick, and so on to the top of the kiln. It is then closed in, as usual. The kiln thus formed when fired requires no further stoking or attention until it burns out, and the building and burning go on together at the same time at the pleasure of the builder.

Having thus described my invention, I claim as new therein and desire to secure by Letters Patent—

The process in the manufacture of brick, which consists in placing a layer of fuel—such as coal, brea, or crude petroleum—upon the floor of the kiln, which floor of the kiln is made to incline toward the center, placing a layer of brick in zigzag rows, each brick and row being slightly separated to form interstices between the brick, filling such interstices with similar fuel used to form the first layer, and covering the brick with said fuel to form a bed for the second layer of brick, again placing a layer of brick in zigzag rows, with interstices between the brick and rows, upon the second bed of fuel, again filling such interstices with fuel and forming a third bed of fuel, and so on, alternately forming a bed of fuel and layer of brick in zigzag rows with interstices between the same until the top of the kiln is reached, the interstices between the brick in each succeeding layer decreasing in width as the pile approaches the top of the kiln, where they disappear, as and for the purposes described and shown.

JAMES M. JAMESON.
